UNITED STATES PATENT OFFICE.

ALVAH D. HADSEL, OF PHILADELPHIA, PENNSYLVANIA, ASSIGNOR TO CABLE EXCAVATOR COMPANY, OF PHILADELPHIA, PENNSYLVANIA, A CORPORATION OF DELAWARE.

CABLE EXCAVATOR.

1,170,484.

Specification of Letters Patent.

Patented Feb. 1, 1916.

Application filed September 10, 1915. Serial No. 49,934.

To all whom it may concern:

Be it known that I, ALVAH D. HADSEL, a citizen of the United States, and a resident of Philadelphia, in the county of 5 Philadelphia and State of Pennsylvania, have invented a new and Improved Cable Excavator, of which the following is a full, clear, and exact description.

This invention relates to excavators of 10 the elevated carrier type or that species of excavators in which the skip or digging and carrying element is movable along an overhead cableway.

Among the objects of the invention is to 15 provide, in combination with a slack cable trackway adapted to be raised or lowered and tightened or slackened, a special and novel type of bucket adapted to be dumped, either automatically or semi-automatically 20 by simple manipulation of the power attachments.

More definitely stated, an object of the invention is to provide a slack cable trackway, trolley devices movable along the 25 trackway, and a bucket suspended at some distance below the trolley devices, the supporting means for the bucket being connected at both ends thereof and leading thence to the trolley devices, means being 30 provided as a result of certain manipulations of the power devices to vary the relative lengths of said suspending devices, whereby the bucket will be tilted for dumping.

With the foregoing and other objects in view, the invention consists in the arrangement and combination of parts hereinafter described and claimed, and while the invention is not restricted to the exact details of 40 construction disclosed herein, still for the purpose of illustrating a practical embodiment thereof reference is had to the accompanying drawings, in which like reference characters designate the same parts in the 45 several views, and in which—

Figure 1 is a side elevation in diagram of one form of the invention, the bucket being shown in full lines in filling position and in dotted lines in dumping position; Fig. 2 is a similar view of a slightly modified form of the invention; Fig. 3 is an en-

larged side elevation of one form of the bucket, in filling position; Fig. 4 is a side elevation of the same in approximately dumping position; Fig. 5 is a side elevation 55 in filling position of that form of bucket shown in Figs. 1 and 2; and Fig. 6 is a side elevation of the same in dumping position.

Referring now more particularly to the drawings, I show a slack cable excavator, 60 and by the term excavator as used herein I would be understood as comprehending other specific types of elevated or overhead carriers, since in many features of the invention the novelty does not depend upon 65 the use of the improvement as an earth digger or excavator. For instance, the apparatus with little or no alteration could well be adapted for handling sugar cane, 70 hay, or various other commodities.

Referring to Figs. 3 and 4 of the drawings, at A I indicate an overhead cableway, which, as heretofore, may comprise a single cable or more, spanning the field of operation.

At 18 I show a bucket indicated as of a self-filling or digging nature of more or less conventional form *per se*, the same, however, being shown as suspended from trolley devices including front and rear trolleys 19 and 20 respectively, movable along the cableway A. One of the suspending devices above referred to consists of a link or bail 21 pivoted at its upper end at 22 to the trolley 19 and at its lower end at 23 75 to the front upper corner of the bucket. The bail 21 is rigid and maintains the points 22 and 23 at a fixed distance apart. The other suspending device for the bucket comprises a cable B connected at one end at 24 to the rear end of a rigid strut 25 and at 80 its other end to the rear end of the bucket at 26. The strut 25 is pivoted at its front end at 27 to the front trolley and extends thence rearwardly along or within the rear 85 trolley 20. The intermediate portion of the suspending cable B operates over a sheave 28 journaled in the bottom of the trolley 20; otherwise there is no direct connection between the rear trolley and either the 90 bucket or the front trolley.

C indicates a draft cable operating from

any suitable source of power. The end of the draft cable is connected to the bucket through a main chain connection 31 connected to the mouth or front portion of the 5 bucket at the point 32, and 33 indicates an auxiliary connection leading from the point 34 to the rear trolley at the point 35.

The operation of the device thus far described may be briefly set forth as follows:

- 10 With the cableway A slackened the bucket will gravitate downwardly along the cableway to the place for filling. The weight of the rear end of the bucket, furthermore, will tend to hold the bucket in a substantially level position, as shown in Fig. 3, the suspending cable B serving to hold the two trolleys well spaced from each other. At this time the suspending bail 21 extends backwardly somewhat as well as downwardly from the front trolley. The elevation of the bucket and its digging action may be controlled by the degree of tightness of the cableway A. The draft upon the cable C, while the bucket is in the position just described, will cause it to be propelled toward the power station and filled with material. When the bucket is filled, the cableway A will be tightened and thereby cause the bucket to be lifted clear of the ground, 30 the draft upon the cable C continuing to convey the filled bucket to the place of deposit, such place being determined by a stop 36 clamped in any suitable manner to the cableway. When the front trolley impinges 35 against the stop 36, the continued draft upon the cable C acting now primarily through the auxiliary line 33, will draw the rear trolley toward the front trolley, as shown in Fig. 4, thereby causing the strut 25 to project relatively rearwardly from the rear trolley and causing the suspending cable B to lift the rear end of the bucket and dump the load. During this action the draft chain 31 will be comparatively inoperative, the draft 40 thereon being relieved by the front portion of the bucket and bail 21 swinging slightly forwardly around the pivot 22. The dumping of the bucket is effected practically automatically in this operation, and thereafter, 45 upon releasing the power devices, the bucket will automatically right itself and return to be refilled as already described.

In Fig. 1 I indicate an adaptation of the invention in which the power station 10 55 is provided with three independently controllable power drums 17, 29' and 17'. This power station is provided with sheaves 13, 30 and 16, and in addition thereto there are provided sheaves 37 and 38 journaled around 60 fixed axes adjacent the top of the tower. The distant support 11 is provided with a sheave 39 at its top. In this arrangement is indicated a cableway A' comprising preferably a pair of cables connected at 12' to the distant tower and operating over the

sheaves 13 around an equalizing pulley 40 secured to the follower block 14. The cable 15 controls the action of the follower block as above described, running over the sheave 16 and connected to the drum 17. Both parts 70 of the cableway A', by virtue of the equalizing pulley 40, are always maintained at equal tension and the degree of tautness thereof is determined through operation of the drum 17.

The trolley devices comprise a frame 41 having wheels 42 rolling on the several parts of the cableway. A bucket 18' is or may be practically the same in form or design as the one previously described. The suspension 80 bail 21, as in the previous description, is pivoted at 22 to the front part of the frame 41 and at 23 to the upper front portion of the bucket. The draft cable C' operates over the sheave 30 and is connected to the drum 29' which is adapted to be reversed or driven in either direction. This draft cable is connected to the bucket and trolley devices through connections comprising a main draft chain 31 and an auxiliary connection 33 secured to the front portion of the bucket and the front portion of the frame 41 respectively.

B' indicates a tail and dumping rope secured in any suitable manner to the drum 29', or it may in some instances constitute a continuation of the draft cable C'. From the drum this rope operates over the sheave 38; thence down forming a loop in which is located a movable sheave 43; thence it extends over the sheave 37 out along the trolley devices between guide rollers 44 carried by a bracket 45 on the frame 41, and thence over the sheave 39 and down again to the bucket over a sheave 28' to the point of connection 105 26 at the back end of the bucket. This rope 110 B' serves, as above set forth, as one of the suspending devices for the bucket and therefore acts not only as a means for dumping the bucket, but it also acts as a tail rope 115 whereby the bucket may be drawn positively along the cableway in the direction opposite from that in which it is drawn by the main draft cable C'.

The operation of filling the bucket and 115 transporting it to the place of deposit of the material is practically the same in this form of the invention as in the first one described, the cableway being adapted to be lifted or lowered by operation of the drum 120 17. The main drum 29' when operated to fill the bucket and draw it toward the power station serves to pay out the rope B' to a similar extent so that the rope B does not obstruct or interfere with the operation of 125 the bucket during these parts of the operation. The rope B', however, is adapted to be manipulated independently of the operation of the cable C', either while the bucket is in motion or otherwise, by operation of 130

the drum 17' having a short looped cable 44' extending therefrom to the block in which the movable sheave 43 is journaled and whereby the depending loop of the rope may be lengthened or shortened. When the loop is thus lengthened or the movable sheave 43 is drawn downwardly, the effective length of the suspension portion of the rope B' is shortened, as shown in Fig. 6, causing the bucket to tilt and dump its contents. This auxiliary drum 17' may also be operated slightly to compensate for the variations in general length of the draft cable and tail rope coincidentally with the tightening or loosening of the cableway.

The bucket shown in Fig. 2 is the same as that in Figs. 1, 5 and 6, and likewise the draft connections C', 31 and 33 are the same. The draft cable, however, in this form of the invention, is operated and controlled by its own individual drum 29. The tail rope B' is connected to and controlled by an independent drum 17" and extends thence over a head sheave, but otherwise it is connected and operates with respect to the bucket the same as in Fig. 1.

In all forms of the invention shown, the filling operation is effected automatically and the dumping is caused by bringing about a variation in the normal strains upon the draft and suspending devices. In those forms of the invention where a tail rope is used, it is possible to transport the filling bucket in either direction along the cableway and dump the contents either between the pit or place of filling and the power station, or between the pit and the remote tower. The transporting is accomplished in either direction by positive draft upon one cable or rope and a substantial paying out of the other at equal speeds, and when the dump is reached the tail rope is caused to operate relatively faster than the draft cable, causing the tilting of the bucket.

45 I claim:

1. In a cable excavator, the combination with an overhead trackway, a bucket, and trolley means operating over the trackway, of suspending devices between the trolley means and the bucket, said suspending devices including a rigid member connected at its ends through fixed pivots to the trolley devices and to the front end of the bucket and a flexible member connected to the other end of the bucket, and means to traverse the bucket and trolley means along the trackway.

2. In a cable excavator, the combination with a trackway, trolley devices operating along the trackway, and a bucket, of suspending devices connecting the bucket to the trolley devices, said suspending devices including a rigid member pivoted to the upper front portion of the bucket and to the front portion of the trolley devices and also in-

cluding a flexible connecting member leading from the rear end of the bucket over the rear portion of the trolley devices, and draft connections including main and auxiliary parts connected respectively to the bucket 70 and trolley devices.

3. In a cable excavator, the combination with a trackway, trolley devices thereon, and a bucket below the trolley devices, of suspending devices for the bucket comprising 75 a rigid member pivoted at one end to the front end of the bucket and extending thence to and pivoted at its other end upon the front portion of the trolley devices and also including a flexible member connected to 80 the rear end of the bucket and extending thence upwardly and along the rear portion of the trolley devices, and means to shorten the effective length of the last mentioned connection to tilt the bucket for dumping its 85 contents.

4. In a cable excavator, the combination with an overhead trackway, a bucket, and a plurality of trolley devices operating along said trackway and movable toward or from 90 each other, of suspending devices between the trolley devices and the bucket, said suspending devices including independent members connected to the respective ends of the bucket, one of said members being connected directly 95 to one of said trolley devices, the other of said members being flexible and operating over a pulley on the other trolley device, and a rigid strut connected at one end to the first mentioned trolley device and extending 100 thence along the other trolley device and having said flexible suspending member connected to the opposite end thereof.

5. In a cable excavator, the combination with an overhead trackway, a bucket, and a 105 plurality of trolley devices operating over the trackway, of suspending devices between the trolley devices and the bucket, said suspending devices including a rigid link pivoted through fixed pivots at its ends to 110 the front trolley device and the front end of the bucket, a flexible connection attached to the rear end of the bucket and extending thence over the rear trolley device, and a rigid strut connected permanently at one end 115 to the front trolley device, extending thence along the rear trolley device and having said flexible member connected to its rear end, and draft members connected to the front end of the bucket and the rear trolley device. 120

6. In a cable excavator, the combination with an overhead trackway, a bucket, and a pair of independently movable trolley devices operating over the trackway, of suspending devices between the bucket and both 125 of said trolley devices, said suspending devices comprising a pair of rigid members permanently connected to the front trolley device and extending thence severally to the front end of the bucket and to the rear trolley 130

device; and a flexible member connected to the rear end of the bucket and extending thence over the rear trolley device and connected to the rear end of the other rigid member, a draft cable, and independent draft connections leading from the draft cable to the front end of the bucket and to

the rear trolley device substantially as set forth.
